COMBINED PICTURE FRAME AND HOLDER FOR MEMO PAPERS

Leonard Rice, 3334 S. Winona Court,
Denver, Colo. 80219

Filed Mar. 30, 1966, Ser. No. 1,854

Term of patent 14 years

(Cl. D74—1)

FIG. 2.

FIG. 5.

FIG. 3.

FIG. 4.

FIG. 1 is a front perspective view of a combined picture frame and holder for memo papers showing my new design;

FIG. 2 is a top plan view thereof;

FIG. 3 is a front elevational view thereof;

FIG. 4 is a side elevational view thereof; and

FIG. 5 is a cross sectional view taken on line 5—5 of FIG. 2, the transparent front panel being omitted for convenience or illustration.

I claim:

The ornamental design for a combined picture frame and holder for memo papers, as shown.
